(57) **ABSTRACT**

A coil component includes a wire including a linear central conductor and an insulating coating layer that covers a circumferential surface of the central conductor, and a terminal electrode that is electrically connected to the central conductor at an end portion of the wire. The terminal electrode includes a receiving portion to which the central conductor is welded. A weld nugget portion that is produced when the central conductor is welded and the receiving portion are welded to each other.

CROSS-REFERENCE TO RELATED APPLICATION

This application claims benefit of priority to Japanese Patent Application No. 2017-042938, filed Mar. 7, 2017, the entire content of which is incorporated herein by reference.

BACKGROUND

Technical Field

This disclosure relates to a coil component, and more particularly, to a connection structure between a wire and a terminal electrode.

Background Art

Japanese Patent No. 4184394 discloses a coil component as shown, for example, in FIGS. 12-14 that correspond to FIGS. 2, 4, and 5, respectively, of Japanese Patent No. 4184394. FIGS. 12 to 14 illustrate a flange portion 71 that is a part of a core included in the coil component, a terminal electrode 72 that is disposed thereon, and an end portion of a wire 73 that is connected to the terminal electrode 72.

As illustrated in FIGS. 12 and 14, the wire 73 includes a linear central conductor 74 and an insulating coating layer 75 that covers the circumferential surface of the central conductor 74. The terminal electrode 72 includes a base 77 that is disposed on an outer end surface 76 of the flange portion 71, and a receiving portion 79 that extends from the base 77 across a bent portion 78 and that receives the end portion of the wire 73. As also illustrated in FIG. 12, the terminal electrode 72 also includes a weld piece 81 that extends from the receiving portion 79 across a first folded portion 80 and that is welded to the central conductor 74 of the wire 73, and a holding portion 83 that extends from the receiving portion 79 across a second folded portion 82 and that holds the wire 73 for positioning.

FIG. 12 illustrates a state before the weld piece 81 is welded. FIGS. 13 and 14 illustrate a state after the weld piece 81 is welded. FIGS. 13 and 14 also illustrate an expanding portion 84 that is produced by welding. The expanding portion 84, which is also referred to as a melt ball, is produced such that a molten metal is formed into a ball shape due to surface tension during welding and is cooled and solidified.

A welding process will now be described in detail. Before the welding process, the weld piece 81 and the holding portion 83 are not bent toward the receiving portion 79 of the terminal electrode 72 and do not face the receiving portion 79. FIG. 12 further illustrates a state where the holding portion 83 faces the receiving portion 79, and the weld piece 81 is not bent toward the receiving portion 79.

The wire 73 is first placed on the receiving portion 79 of the terminal electrode 72. To maintain this state, the holding portion 83 is bent from the second folded portion 82 toward the receiving portion 79 such that the wire 73 is interposed between the receiving portion 79 and the holding portion 83.

Subsequently, as illustrated in FIG. 12, a portion of the insulating coating layer 75 of the wire 73 on the side nearer than the holding portion 83 to the end is removed. The insulating coating layer 75 is removed by using, for example, laser beam radiation. As also illustrated in FIG. 14, a portion of the insulating coating layer 75 in contact with the receiving portion 79 is not removed and remains.

2

Subsequently, the weld piece 81 is bent from the first folded portion 80 toward the receiving portion 79, and the wire 73 is interposed between the weld piece 81 and the receiving portion 79. Afterward, the central conductor 74 of the wire 73 and the weld piece 81 are welded to each other. More specifically, laser beam welding is used. The weld piece 81 is irradiated with a laser beam, and the central conductor 74 of the wire 73 and the weld piece 81 are thereby melted. Liquefied weld nugget portion is formed into a ball shape due to surface tension. Consequently, the expanding portion 84 is formed as described above.

During the above welding process, the molten metal protrudes from the receiving portion 79 of the terminal electrode 72 and reaches the bent portion 78 or the base 77 in some cases. Consequently, heat due to such excessive welding adversely affects the core forming the flange portion 71 in some cases, and, for example, the heat causes the flange portion 71 to melt.

According to the technique disclosed in Japanese Patent No. 4184394, the portion of the insulating coating layer 75 in contact with the receiving portion 79 is not removed and remains as described above to prevent the above excessive welding.

SUMMARY

According to the above technique disclosed in Japanese Patent No. 4184394, the insulating coating layer 75 is used to prevent the excessive welding. From a different viewpoint, however, the central conductor 74 of the wire 73 is welded to a limited portion (weld piece 81) of the terminal electrode 72. For this reason, reliability of connection of the wire 73 is low, and a joint between the wire 73 and terminal electrode 72 is likely to be weakened when a physical external force is applied to, for example, the expanding portion 84.

There is a case where it is not necessary to be concerned about heat transferred from the receiving portion 79 to the flange portion 71 due to excessive welding, for example, when the receiving portion 79 is not in contact with the flange portion 71. In this case, the entire circumference of the central conductor 74 is to be welded to the terminal electrode 72 in a manner in which the central conductor 74 is welded to not only the weld piece 81 but also the receiving portion 79. This is better than the case where the central conductor 74 is welded to only the weld piece 81 from the viewpoint that a higher mechanical strength, a lower electric resistance, and higher reliability are achieved.

However, according to the technique disclosed in Japanese Patent No. 4184394, the insulating coating layer 75 is interposed between the central conductor 74 and the receiving portion 79. Herein lies a problem because the central conductor 74 and the receiving portion 79 are prevented from being welded to each other even when the entire circumference of the central conductor 74 is to be welded to the terminal electrode 72. This leads to a decrease in the mechanical strength and reliability of the welded portion and an increase in electric resistance and is not preferable.

In view of this, the disclosure provides a coil component that has increased reliability of electric and mechanical connection between the central conductor of the wire and the terminal electrode.

According to one embodiment of the present disclosure, a coil component includes a wire including a linear central conductor and an insulating coating layer that covers a circumferential surface of the central conductor, and a terminal electrode that is electrically connected to the central

conductor at an end portion of the wire. The terminal electrode includes a receiving portion along the end portion of the wire. A weld nugget portion is integrally formed of the central conductor and the terminal electrode on the end portion of the wire. The receiving portion and the weld nugget portion are welded to each other.

In the coil component, the receiving portion and the weld nugget portion are in contact with each other, and the central conductor of the wire is located between the receiving portion and the weld nugget portion. In the coil component, the central conductor is preferably welded to the receiving portion and the weld nugget portion at the end portion of the wire. With this structure, a higher mechanical strength, a lower electric resistance, and higher reliability for a high stress resistance can be achieved with more certainty.

In the coil component, the weld nugget portion preferably does not contain a substance originated from the insulating coating layer. In the case where the insulating coating layer 75 is interposed between the central conductor 74 and the receiving portion 79 as in the technique disclosed in Japanese Patent No. 4184394 and described with reference to FIGS. 12 to 14, the insulating coating layer 75 is considerably affected by welding heat. For this reason, in some cases, substances such as carbide originated from the insulating coating layer 75 are produced due to the welding heat, spread over the expanding portion 84, and cause blowholes to be formed. However, the above structure prevents the substances such as carbide originated from the insulating coating layer due to the welding heat from spreading into the weld nugget portion, and prevents the formation of blowholes.

In the coil component, the insulating coating layer is more preferably removed from an entire circumference of the end portion of the wire. With this structure, the weld nugget portion that does not contain the substance originated from the insulating coating layer can be obtained with certainty.

The coil component preferably further includes a core including a winding core portion and a flange portion that is disposed on an end portion of the winding core portion. The wire is preferably helically wound around the winding core portion. The terminal electrode is preferably attached on the flange portion. With this structure, the weld nugget portion is located on the opposite side (on the outer side portion of the component) of the wire from the flange portion, and accordingly, a welding process can be readily performed.

In the coil component, the receiving portion is more preferably located at a predetermined spacing from the flange portion. With this structure, increased heat during the welding process is unlikely to be transferred from the receiving portion to the flange portion, and an adverse effect on the core due to heat can be decreased.

In the coil component according to some embodiments of the present disclosure, the receiving portion and the weld nugget portion are welded to and in contact with each other, the central conductor of the wire is located between the receiving portion and the weld nugget portion and contained in the weld nugget portion. Accordingly, a welded portion of the wire can have a high mechanical strength, and reliability of electrical connection can be increased.

Other features, elements, characteristics and advantages of the present disclosure will become more apparent from the following detailed description with reference to the attached drawings.

BRIEF DESCRIPTION OF THE DRAWINGS

FIG. 1A is a perspective view of a common-mode choke coil as a coil component according to an embodiment in the disclosure when viewed from a relatively upper position;

FIG. 1B is a perspective view of the common-mode choke coil when viewed from a relatively lower position;

FIG. 2A is a front view of the common-mode choke coil illustrated in FIGS. 1A and 1B;

5 FIG. 2B is a bottom view of the common-mode choke coil;

FIG. 2C is a left-side view of the common-mode choke coil;

10 FIG. 3 is an enlarged sectional view of a wire that the common-mode choke coil illustrated in FIGS. 1A and 1B includes;

FIGS. 4A and 4B illustrate a process of electrically connecting the wire to a terminal electrode in the common-mode choke coil illustrated in FIGS. 1A and 1B;

15 FIG. 5 illustrates a picture of an electrical receiving portion between the wire and the terminal electrode of an actual product of the common-mode choke coil that is taken from the front direction;

20 FIG. 6 illustrates a picture of an enlarged section of the electrical contact between the wire and the terminal electrode illustrated in FIG. 5;

FIG. 7 is a diagram that is drawn by tracing the picture illustrated in FIG. 6 and that is used to describe the picture in FIG. 6;

25 FIG. 8A schematically illustrates an edge portion of the terminal electrode and the wire pulled near the edge portion in the case of the common-mode choke coil illustrated in FIGS. 1A and 1B according to the embodiment in the disclosure;

30 FIG. 8B schematically illustrates an edge portion of a terminal electrode and a wire pulled near the edge portion in the case of an example of an existing common-mode choke coil;

FIGS. 9A to 9D illustrate a process of obtaining the 35 terminal electrode having the edge portion illustrated in FIG. 8A;

FIG. 10 illustrates a modification to the edge portion of the terminal electrode and corresponds to FIG. 8A;

40 FIG. 11 illustrates another modification to the edge portion of the terminal electrode and corresponds to FIG. 8A;

FIG. 12 is a perspective view of the flange portion of the core, the terminal electrode disposed thereon, and the wire connected to the terminal electrode that are included in the coil component disclosed in Japanese Patent No. 4184394 in a state before a welding process;

45 FIG. 13 is a perspective view of the portions illustrated in FIG. 12 in a state after the welding process; and

FIG. 14 is a sectional view of the portions illustrated in FIG. 13.

DETAILED DESCRIPTION

To describe a coil component according to the disclosure, a common-mode choke coil is taken as an example of the coil component. A common-mode choke coil 1 as a coil component according to an embodiment in the disclosure will be described with reference to mainly FIGS. 1A and 1B, and FIGS. 2A to 2C.

The common-mode choke coil 1 includes a ferrite core 3 including a winding core portion 2. The ferrite core 3 has a drum shape and includes first and second flange portions 4 and 5 that are respectively disposed on first and second end portions of the winding core portion 2 that are opposite each other. The common-mode choke coil 1 also includes a ferrite plate 6 that extends over the first and second flange portions 4 and 5. The ferrite core 3 may be replaced with a core formed of a material other than ferrite.

The Curie temperature of the ferrite core **3** is preferably 150° C. or more because an inductance value can be maintained at a predetermined value or more at between a low temperature and 150° C. The relative permeability of the ferrite core **3** is preferably 1500 or less. With this configuration, it is not necessary to use a special structure and material of the ferrite core **3** with high magnetic permeability. Accordingly, the degree of freedom of design of the ferrite core **3** is improved, and the ferrite core **3** having, for example, a Curie temperature of 150° C. or more can be readily designed. Thus, the above configuration enables the common-mode choke coil **1** to ensure the inductance value at a high temperature and to have good temperature characteristics.

The Curie temperature of the ferrite plate **6** is preferably 150° C. or more. The relative permeability of the ferrite plate **6** is preferably 1500 or less.

The flange portions **4** and **5** each have inner end surfaces **7** and **8** that face the winding core portion **2**, and outer end surfaces **9** and **10** that are opposite the inner end surfaces **7** and **8** and that face outward, and end portions of the winding core portion **2** are disposed on the inner end surfaces **7** and **8**. The flange portions **4** and **5** each have lower surfaces **11** and **12** that are to face a mounting substrate side (not illustrated) during mounting and upper surfaces **13** and **14** that are opposite the lower surfaces **11** and **12**. The ferrite plate **6** is joined to the upper surfaces **13** and **14** of the flange portions **4** and **5**. The first flange portion **4** has first and second side surfaces **15** and **16** that extend so as to connect the lower surface **11** and the upper surface **13** to each other and that oppose each other. The second flange portion **5** has first and second side surfaces **17** and **18** that extend so as to connect the lower surface **12** and the upper surface **14** to each other and that oppose each other.

Notch-like depressions **19** and **20** are formed on both end portions of the lower surface **11** of the first flange portion **4**. Similarly, notch-like depressions **21** and **22** are formed on both end portions of the lower surface **12** of the second flange portion **5**.

The common-mode choke coil **1** also includes first and second wires **23** and **24** that are helically wound around the winding core portion **2**. In FIGS. 1A and 1B and FIGS. 2A to 2C, end portions of the wires **23** and **24** are illustrated but portions of the wires **23** and **24** around the winding core portion **2** are omitted. As the wire **23** is illustrated in FIG. 3, the wires **23** and **24** each include a linear central conductor **25** and an insulating coating layer **26** that covers the circumferential surface of the central conductor **25**.

The central conductor **25** is formed of, for example, a copper wire. The insulating coating layer **26** is preferably formed of a resin containing at least an imide linkage such as polyamide imide or imide-modified polyurethane. With this structure, the insulating coating layer can have heat resistance so as not to decompose at, for example, 150° C. Accordingly, a line capacitance does not vary even at a high temperature of 150° C., and Sdd11 characteristics can be improved. In addition, an excellent effect of inhibiting a noise even at a high temperature of 150° C. can be enhanced.

The first and second wires **23** and **24** are wound in the same direction in parallel. The wires **23** and **24** may be wound so as to form two layers such that any one of the wires **23** and **24** is wound on an inner layer side and the other is wound on an outer layer side. The wires **23** and **24** may be wound in a bifilar winding manner such that the wires **23** and **24** are arranged so as to alternate in the axial direction of the winding core portion **2**.

The diameter **D** of the central conductor **25** is preferably 35 μ m or less. With this configuration, since the diameter of the wires **23** and **24** can be decreased, the number of turns of the wires **23** and **24** wound around the winding core portion **2** can be increased, the miniaturization can be achieved without changing the number of turns of the wires **23** and **24**, and a clearance between the wires can be increased without changing the wires **23** and **24** and a coil shape. A decrease in the percentage of the wires **23** and **24** in the coil shape enables dimensions of other components, such as the ferrite core **3**, to be increased and further improves the characteristics.

The diameter **D** of the central conductor **25** is preferably 28 μ m or more. With this configuration, disconnection of the central conductor **25** is unlikely to occur.

The thickness **T4** of the insulating coating layer **26** is preferably 6 μ m or less. With this configuration, since the diameter of the wires **23** and **24** can be decreased, the number of turns of the wires **23** and **24** wound around the winding core portion **2** can be increased, the miniaturization can be achieved without changing the number of turns of the wires **23** and **24**, and the clearance between the wires can be increased without changing the wires **23** and **24** and the coil shape. A decrease in the percentage of the wires **23** and **24** in the coil shape enables dimensions of other components, such as the ferrite core **3**, to be increased and further improves the characteristics.

The thickness **T4** of the insulating coating layer **26** is preferably 3 μ m or more. With this configuration, the distance between the central conductors **25** of the wires **23** and **24** that are adjacent to each other in a winding state can be increased. Accordingly, the line capacitance is decreased, and the Sdd11 characteristics can be improved.

The common-mode choke coil **1** also includes first to fourth terminal electrodes **27** to **30**. The first and third terminal electrodes **27** and **29** of the first to fourth terminal electrodes **27** to **30** are arranged in the direction in which the first and second side surfaces **15** and **16** oppose each other and are attached on the first flange portion **4** by using an adhesive. The second and fourth terminal electrodes **28** and **30** are arranged in the direction in which the first and second side surfaces **17** and **18** oppose each other and are attached on the second flange portion **5** by using an adhesive.

The first terminal electrode **27** and the fourth terminal electrode **30** have the same shape. The second terminal electrode **28** and the third terminal electrode **29** have the same shape. The first terminal electrode **27** and the third terminal electrode **29** are symmetric with each other with respect to a plane. The second terminal electrode **28** and the fourth terminal electrode **30** are symmetric with each other with respect to a plane. Accordingly, one terminal electrode of the first to fourth terminal electrodes **27** to **30**, for example, the first terminal electrode **27** that is best illustrated in FIG. 1A and FIG. 1B will be described in detail, and a detailed description of the second, third, and fourth terminal electrodes **28**, **29**, and **30** is omitted.

The terminal electrode **27** is typically manufactured in a manner in which a metallic plate formed of a copper alloy such as phosphor bronze or tough pitch copper is subjected to a progressive stamping process and a plating process. The terminal electrode **27** has a thickness of 0.15 mm or less, for example, a thickness of 0.1 mm.

As well illustrated in FIG. 1B, the terminal electrode **27** includes a base **31** that extends along the outer end surface **9** of the flange portion **4**, and a mounting portion **33** that extends from the base **31** along the lower surface **11** of the flange portion **4** across a first bent portion **32** that covers a

ridge line along which the outer end surface 9 and the lower surface 11 of the flange portion 4 meet. When the common-mode choke coil 1 is mounted on the mounting substrate, not illustrated, the mounting portion 33 is to be electrically and mechanically connected to a conductive land on the mounting substrate by, for example, soldering.

Referring to FIG. 1B, the terminal electrode 27 also includes a rising portion 35 that extends from the mounting portion 33 across a second bent portion 34 and a receiving portion 37 that extends from the rising portion 35 across a third bent portion 36. The rising portion 35 extends along a vertical wall 38 that defines the depression 19. The receiving portion 37 extends along a bottom surface wall 39 that defines the depression 19. The receiving portion 37 is along an end portion of the wire 23 and is a portion at which the wire 23 is electrically and mechanically connected to the terminal electrode 27.

The receiving portion 37 is preferably located at a predetermined spacing from the flange portion 4. More specifically, it is preferable that the rising portion 35 and the receiving portion 37 be located at a predetermined spacing from the vertical wall 38 and the bottom surface wall 39 that define the depression 19 and be in contact with neither the vertical wall 38 nor the bottom surface wall 39.

The reference numbers 31, 32, 33, 34, 35, 36, and 37 that are used to denote the base, the first bent portion, the mounting portion, the second bent portion, the rising portion, the third bent portion, and the receiving portion of the first terminal electrode 27 are also used to denote the base, the first bent portion, the mounting portion, the second bent portion, the rising portion, the third bent portion, and the receiving portion of the second, third, and fourth terminal electrodes 28, 29, and 30 as needed.

A first end of the first wire 23 is electrically connected to the first terminal electrode 27. A second end of the first wire 23 opposite the first end is electrically connected to the second terminal electrode 28. A first end of the second wire 24 is electrically connected to the third terminal electrode 29. A second end of the second wire 24 opposite the first end is electrically connected to the fourth terminal electrode 30.

The wires 23 and 24 are typically wound around the winding core portion 2 before the wires 23 and 24 and the terminal electrodes 27 to 30 are connected to each other. During a winding process, the ferrite core 3 is rotated about the central axis of the winding core portion 2, and, in this state, the wires 23 and 24 are caused to traverse from a nozzle and supplied toward the winding core portion 2. Thus, the wires 23 and 24 are helically wound around the winding core portion 2.

During the winding process, since the ferrite core 3 is rotated as described above, the ferrite core 3 is held by a chuck connected to a rotary drive source. The chuck is configured to hold one of the flange portions of the ferrite core 3, for example, the first flange portion 4.

Attention is paid to the outer end surface 9 of the first flange portion 4. A projecting stepped portion 40 that extends along a ridge line along which the upper surface 13 and the outer end surface 9 meet is formed thereon. A flat surface 41 is formed in a region of the outer end surface 9 that is nearer than a region in which the stepped portion 40 is formed to the lower surface 11.

The terminal electrodes 27 to 30 are attached on the ferrite core 3. The base 31 of the terminal electrode 27 and the base 31 of the terminal electrode 29 are adjacent to each other in the direction in which the first and second side surfaces 15 and 16 oppose each other, and are along the flat surface 41 of the outer end surface 9. As illustrated in FIG. 2C, a

clearance S1 between the base 31 of the terminal electrode 27 and the base 31 of the terminal electrode 29 on the side near the lower surface 11 is larger than a clearance S2 on the side near the upper surface 13 (or the stepped portion 40). According to the embodiment, the two bases 31 each have a T-shape, and accordingly, the clearances satisfying S1>S2 are achieved.

The gripping portion of the chuck holds the ferrite core 3 in a state where the gripping portion is in contact with five portions of the flange portion 4: (1) the first side surface 15, (2) the second side surface 16, (3) the upper surface 13, (4) the stepped portion 40, and (5) a portion of the flat surface 41 having the clearance S1. Accordingly, when the wires 23 and 24 are wound, the posture of the ferrite core 3 that is rotated can be stable.

The clearance S1 between the base 31 of the terminal electrode 27 and the base 31 of the terminal electrode 29 on the side near the lower surface 11 is preferably larger than 0.3 mm. This ensures a sufficient area of contact between the gripping portion of the chuck and the flat surface 41. The clearance S2 on the side near the upper surface 13 is preferably no less than 0.1 mm and no more than 0.3 mm. In the case where the progressive stamping process is performed, it is typically difficult to perform punching with a dimension less than the thickness of the metallic plate as a workpiece. Accordingly, in the case where the thickness of the metallic plate, which is the material of each of the terminal electrodes 27 to 30, is 0.1 mm as described above, the progressive stamping process can be readily performed in a manner in which the clearance S2 is set to be no less than 0.1 mm and no more than 0.3 mm (e.g., from 0.1 mm to 0.3 mm).

When the ferrite core 3 held by the chuck connected to the rotary drive source is rotated about the central axis of the winding core portion 2 as described above, the wires 23 and 24 that are supplied from the nozzle traverse and are helically wound around the winding core portion 2. The number of turns of each of the first and second wires 23 and 24 wound around the winding core portion 2 is preferably 42 turns or less. The reason is that the total length of the wires 23 and 24 can be decreased, and the Sdd11 characteristics can be improved. The number of turns of each of the wires 23 and 24 is preferably 39 turns or more to ensure the inductance value.

The chuck is configured to hold only one of the flange portions, for example, the first flange portion 4 during the winding process, the other flange portion, for example, the second flange portion 5 may not include the stepped portion 40 and the flat surface 41, which the first flange portion 4 includes. The shape and arrangement of the base 31 of each of the second and fourth terminal electrodes 28 and 30 may not be the same as the base 31 of each of the first and third terminal electrodes 27 and 29, which is described above.

However, in the case where the first and second flange portions 4 and 5 and the first to fourth terminal electrodes 27 to 30 have the above characteristic structures, during the winding process, the directionality of the ferrite core 3 can be eliminated, and a directional error when the chuck holds the ferrite core 3 can be eliminated. After the winding process, the wires 23 and 24 and the terminal electrodes 27 to 30 are connected to each other in the following manner.

A process of connecting the first wire 23 to the first terminal electrode 27 will now be representatively described with reference to FIGS. 4A and 4B. FIGS. 4A and 4B schematically illustrate the receiving portion 37 of the first terminal electrode 27 and the end portion of the first wire 23.

Right after the winding process is finished, as illustrated in FIG. 4A, the end portion of the wire 23 is pulled so as to extend along the receiving portion 37 and reach a location on an end portion 37a of the receiving portion 37. The insulating coating layer 26 is removed from the entire circumference of the end portion of the wire 23. The insulating coating layer 26 is removed by using, for example, laser beam radiation.

Subsequently, as illustrated in FIG. 4A, a laser beam 42 for welding is directed toward a region in which the central conductor 25 exposed from the insulating coating layer 26 of the wire 23 overlaps the end portion 37a. Thus, the central conductor 25 and the end portion 37a on which the central conductor 25 is disposed are melted. At this time, as illustrated in FIG. 4B, the central conductor 25 and the end portion 37a that are melted are formed into a ball shape due to surface tension acting thereon, and a weld nugget portion 43 is formed. That is, the weld nugget portion 43 is integrally formed of the central conductor 25 and the terminal electrode 27 (end portion 37a). The central conductor 25 is contained in the weld nugget portion 43.

It is preferable that the receiving portion 37 be located at a predetermined spacing from the flange portion 4 and be not in contact with the flange portion 4 as described above. With this structure, increased heat during the welding process is unlikely to be transferred from the receiving portion 37 to the flange portion 4, and an adverse effect on the ferrite core 3 due to heat can be reduced, although this structure is not essential.

FIG. 5 illustrates a picture of an electrical contact between one of the wires and one of the terminal electrodes of an actual product of the common-mode choke coil that is taken from the front direction. In FIG. 5, a circular portion at the upper right corresponds to a melt ball, that is, the weld nugget portion 43. FIG. 6 illustrates a picture of an enlarged section of the electrical contact between the wire and the terminal electrode illustrated in FIG. 5. FIG. 7 is a diagram that is drawn by tracing the picture illustrated in FIG. 6 and that is used to describe the picture in FIG. 6. In FIGS. 4A and 4B, the laser beam 42 is directed from above to below. This relationship in the vertical direction is opposite to that in FIGS. 5 to 7.

Comparing FIGS. 6 and 7, the weld nugget portion 43 is welded to and in contact with not only the end portion 37a but also a part of the receiving portion 37, which remains after welding, during the welding process. The central conductor 25 of the wire 23 is located between the receiving portion 37 and the weld nugget portion 43 and contained in the weld nugget portion 43. It is preferable that the insulating coating layer 26 be removed from the entire circumference of the end portion of the wire 23 and the central conductor 25 of the wire 23 at the end portion of the wire 23 be welded to the receiving portion 37 and the weld nugget portion 43. The weld nugget portion 43 preferably does not contain a substance originated from the insulating coating layer 26. The receiving portion 37 and the weld nugget portion 43 can be distinguished in a manner in which a portion whose outer edge shape is still a plate shape is regarded as the receiving portion 37 and a portion whose outer edge shape is a curved shape is regarded as the weld nugget portion 43.

In this way, strong welds can be obtained. The central conductor 25 of the wire 23 is located between the receiving portion 37 and the weld nugget portion 43, and the entire circumference thereof is contained in the weld nugget portion 43. Accordingly, a higher mechanical strength, a lower electric resistance, a higher stress resistance, and a higher

chemical corrosion resistance, for example, can be achieved, and higher reliability of the weld structure can be achieved. Since the weld nugget portion 43 does not contain a substance originated from the insulating coating layer 26, blowholes during welding can be reduced. Also in this respect, high reliability of the weld structure can be achieved.

The other terminal electrodes 28 to 30 and the wire 23 or 10 24 are connected in the same manner as in connection between the first terminal electrode 27 and the first wire 23 that is described above.

After the wires 23 and 24 are wound, and the wires 23 and 15 24 are joined to the terminal electrodes 27 to 30, the ferrite plate 6 is joined to the upper surfaces 13 and 14 of the first and second flange portions 4 and 5 by using an adhesive. In this way, the ferrite core 3 and the ferrite plate 6 form a closed magnetic circuit, and accordingly, the inductance value can be improved.

The ferrite plate 6 may be replaced with a magnetic resin 20 plate or a metallic plate that can form the magnetic circuit. The ferrite plate 6 may be omitted from the common-mode choke coil 1.

In the case where a stress due to, for example, thermal 25 expansion and shrinkage is applied to the common-mode choke coil 1 completed in the above manner, or in the case where the wires 23 and 24 are pulled while the common-mode choke coil 1 is being manufactured, there is a possibility that the insulating coating layer 26 is damaged or the central conductor 25 is disconnected at a point at which at 30 least one of the wires 23 and 24 is in contact with at least one of the terminal electrodes 27 to 30. In particular, when the common-mode choke coil 1 is used in a vehicle, a stress due to, for example, thermal expansion and shrinkage is likely to be applied to the common-mode choke coil 1. The contact point can be found, for example, from a place C surrounded by a circle in FIG. 2B.

These circumstances related to the first wire 23 and the 35 first terminal electrode 27 illustrated in FIGS. 8A and 8B will be described in behalf of the wires 23 and 24 and the terminal electrodes 27 to 30.

The terminal electrode 27 is manufactured in a manner in which a metallic plate formed of a copper alloy such as phosphor bronze or tough pitch copper is subjected to the progressive stamping process and the plating process as 40 described above. The metallic plate of the terminal electrode 27 has a thickness of 0.15 mm or less, for example, a thickness of 0.1 mm. In this case, a sharp "droop" or "burr" is likely to be formed on an edge portion 44 of the terminal electrode 27 after press working as a result of shearing with a press. Accordingly, as illustrated in FIG. 8B, when the wire 23 comes into contact with the edge portion 44 on which the sharp "droop" or "burr" is formed, the insulating coating layer 26 is damaged, or the central conductor 25 is disconnected, as described above, in some cases.

55 In view of this, according to the embodiment, as illustrated in FIG. 8A, the edge portion 44 is chamfered. In the case where the edge portion 44 is chamfered, the contact area increases, there are multiple contact points, and even when the wire 23 is in contact with the terminal electrode 27, a load applied from the terminal electrode 27 to the wire 23 is distributed. Accordingly, damage to the insulating coating layer 26 and disconnection of the central conductor 25 are 60 unlikely to occur. Consequently, the central conductor 25 can continue to be appropriately covered by the insulating coating layer 26 at a location of contact between the edge portion 44 and the wire 23 so as not to be exposed from the insulating coating layer 26.

11

The terminal electrode 27 including the edge portion 44 that is chamfered as above is preferably obtained in a manner in which a coining process is added in processes included in the press working.

The detail will be described with reference to FIGS. 9A to 9D. As illustrated in FIG. 9A, a metallic plate 45, which is the material of the terminal electrode 27, is first prepared. Subsequently, as illustrated in FIG. 9B, a coining mold 46 is press-fitted into the metallic plate 45, and a mold pattern is formed on a main surface of the metallic plate 45. In the case where the coining mold 46 has a convex rounded surface 47, a mold pattern having a corresponding concave rounded surface 48 is formed on the metallic plate 45. Subsequently, as illustrated in FIG. 9C, a blanking process based on shearing is performed on the metallic plate 45 by using a punch 49 and a die 50. The metallic plate 45 is cut at a location inside a region of press-fitting by the coining mold 46, and the terminal electrode 27 is obtained.

The chamfered portion at which the concave rounded surface 48 corresponding to the convex rounded surface 47 is formed with the coining mold 46 remains on the edge portion 44 of the obtained terminal electrode 27. The edge portion 44 having the concave rounded surface 48 comes into contact with the wire 23 at two points. The reason is that a region of the edge portion 44 that is interposed between the two points of contact with the wire 23 has the recessed surface.

The edge portion 44 of the terminal electrode 27 illustrated in FIG. 8A is chamfered to form the concave rounded surface 48. However, as illustrated in, for example, FIG. 10, the edge portion 44 may be chamfered to form a recessed surface 51 having a V-shape in section as a modification. In this case, the region of the edge portion 44 that is interposed between the two points of contact with the wire 23 has the recessed surface. The edge portion 44 comes into contact with the wire 23 at two points, and damage to the wire 23 can be decreased.

As illustrated in, for example, FIG. 11, the edge portion 44 may be chamfered to form two recessed surfaces 51 each having a V-shape in section as another modification to the chamfered portion. According to this modification, the number of the points of contact with the wire 23 can be larger than that in the case of the modification illustrated in FIG. 10, and damage to the wire 23 can be further decreased. The number of the points of contact with the wire 23 can be further increased in accordance with the number of the recessed surfaces each having a V-shape in section. Thus, the edge portion 44 is preferably in contact with the wire 23 at multiple points. In this case, the region of the edge portion 44 that is interposed between the multiple points preferably has a recessed surface.

There can be many other modifications to the shape of the chamfered portion. For example, the shape can be changed into a shape in which a V-shaped bent portion of the recessed surface having a V-shape in section has a curved surface, a shape in which the bottom surface of the chamfered portion is not parallel to a main surface of the metallic plate forming the terminal electrode, or another shape. The shape may be changed into, for example, a shape of a convex rounded surface such that the contact area between the wire and the metallic plate forming the terminal electrode is increased.

The chamfer shape can be readily changed in a manner in which the shape of a mold corresponding to the coining mold 46 illustrated in FIG. 9B is changed. However, the chamfering method is not limited to the above additional coining process, provided that the same structure can be obtained.

12

The place C surrounded by the circle in FIG. 2B is described as an example of the edge portion 44 of the terminal electrode 27 in contact with the wire 23. However, the same contact state can be found from other places related to paths on which the wires 23 and 24 are pulled. It is not necessary to chamfer a portion of the terminal electrode 27 that is not in contact with the wire 23. It is preferable that the wire 23 is not in contact with the flange portion 4 from the winding core portion 2 to the terminal electrode 27.

Regarding the external dimensions of the ferrite core 3, as illustrated in FIG. 2B, it is preferable that an external dimension L1 that is measured in the axial direction of the winding core portion 2 be 3.4 mm or less, and an external dimension L2 that is measured in a direction perpendicular to the axial direction of the winding core portion 2 be 2.7 mm or less in order to miniaturize the common-mode choke coil 1. With this configuration, the miniaturization of the common-mode choke coil 1 enables the common-mode choke coil 1 to be located nearer a low EMC component and improves a substantial effect of inhibiting a noise. In the case where the volume of the ferrite core 3 is a predetermined volume or less, the absolute amount of expansion and shrinkage of the ferrite core 3 due to heating and cooling can be decreased, and a variation in the characteristics at between a low temperature and a high temperature can be decreased.

As illustrated in FIG. 2A, the thicknesses T1 and T2 of the first and second flange portions that are measured in the axial direction of the winding core portion 2 are preferably less than 0.7 mm. With this configuration, the length of the winding core portion 2 in the axial direction can be increased within the limited range of the external dimensions L1 and L2 of the common-mode choke coil 1. This means that the degree of freedom of the way in which the wires 23 and 24 are wound is increased. For this reason, the number of turns of the wires 23 and 24 can be increased, and consequently, the inductance value can be increased, or the thickness of the wires 23 and 24 to be wound can be increased, consequently, disconnection of the wires 23 and 24 is unlikely to occur, and the direct current resistance of the wires 23 and 24 can be decreased. An increase in the clearance between the wires (thickness of the insulating coating) decreases the line capacitance.

In a state where the common-mode choke coil 1 is mounted on the mounting surface, the area of each of the first and second flange portions 4 and 5 that is projected on the mounting surface, that is, the area of each of the flange portions 4 and 5 illustrated in FIG. 2B is preferably less than 1.75 mm². With this configuration, the length of the winding core portion 2 in the axial direction can be increased within the limited range of the external dimensions L1 and L2 of the common-mode choke coil 1 as in the above case, and accordingly, the same effects as in the above case can be expected.

The sectional area of the winding core portion 2 is preferably less than 1.0 mm². With this configuration, the total length of the wires 23 and 24 can be decreased while the number of turns of the wires 23 and 24 is maintained, and accordingly, the Sdd11 characteristics can be improved.

In a state where the common-mode choke coil 1 is mounted on the mounting surface, the distance between the winding core portion 2 and the mounting surface, that is, a distance L3 illustrated in FIG. 2A is preferably 0.5 mm or more. With this configuration, the distance between a ground pattern that can be formed on the mounting surface side and each of the wires 23 and 24 wound around the winding core portion 2 can be increased, a stray capacitance between the

13

ground pattern and each of the wires 23 and 24 can be decreased, and accordingly, mode conversion characteristics can be improved.

As illustrated in FIG. 2A, the thickness T3 of the ferrite plate 6 is preferably 0.75 mm or less. With this configuration, the total height of the common-mode choke coil 1 can be decreased, or the height position of the winding core portion 2 can be a higher position away from the mounting surface without increasing the total height of the common-mode choke coil 1. Consequently, the stray capacitance between the ground pattern on the mounting surface side and each of the wires 23 and 24 can be decreased, and accordingly, the mode conversion characteristics can be improved.

The clearance between each of the first and second flange portions 4 and 5 and the ferrite plate 6 is preferably 10 μm or less. With this configuration, the magnetic resistance of the magnetic circuit formed by the ferrite core 3 and the ferrite plate 6 can be decreased, and accordingly, the inductance value can be increased. The clearance between each of the first and second flange portions 4 and 5 and the ferrite plate 6 can be obtained, for example, in a manner in which a sample of the common-mode choke coil 1 is polished such that an end surface of one of the flange portions 4 and 5 becomes flat, the clearance of the sample is measured in the width direction (direction of L2 in FIG. 2B) at five points that are at regular intervals, and the arithmetic mean of the measured values is calculated.

The common-mode choke coil 1 described above is characterized in that the common-mode inductance value at 150° C. and 100 kHz is 160 μH or more, and the return loss at 20° C. and 10 MHz is -27.1 dB or less. In the case where the common-mode inductance value is 160 μH or more, a common-mode rejection ratio of -45 dB or less, which is noise removal performance required for high speed communication such as BroadR-Reach, can be satisfied. The common-mode choke coil 1 have improved bandpass characteristics of communication signals during the high speed communication and ensures the quality of the communication. In particular, a return loss of -27 dB or less enables the communication to be performed without problems. Moreover, a return loss of -27.1 dB or less enables high speed communication with higher quality to be achieved. Accordingly, the common-mode choke coil 1 enables at least high speed communication to be performed at a higher temperature and achieves high speed communication with higher quality at a normal temperature.

In the common-mode choke coil 1, the return loss at 130° C. and 10 MHz is preferably -27 dB or less. With this configuration, the common-mode choke coil 1 can achieve the communication in a wider temperature range without problems.

The coil component according to the disclosure is described above on the basis of the more specific embodiment of the common-mode choke coil. The embodiment is described by way of example, and other various modifications can be made.

For example, the number of the wires included in the coil component, the winding direction of the wires, and the number of the terminal electrodes, for example, can be changed in accordance with the function of the coil component.

According to the embodiment, laser beam welding is used to connect the terminal electrodes and the wires. However, the embodiment is not limited thereto, and arc welding may be used. Also, the coil component according to the disclosure may not include the core.

14

While some embodiments of the disclosure have been described above, it is to be understood that variations and modifications will be apparent to those skilled in the art without departing from the scope and spirit of the disclosure. The scope of the disclosure, therefore, is to be determined solely by the following claims.

What is claimed is:

1. A coil component comprising:
a wire including a linear central conductor and an insulating coating layer that covers a circumferential surface of the central conductor; and
a terminal electrode that is electrically connected to the central conductor at an end portion of the wire,
wherein the terminal electrode includes a receiving portion along the end portion of the wire, a weld nugget portion is integrally formed of the central conductor and the terminal electrode on the end portion of the wire, and the receiving portion and the weld nugget portion are welded to each other,
the welded material consists of only the materials of the central conductor and the receiving portion,
the receiving portion has a first surface where the end portion of the wire is mounted and a second surface opposite to the first surface;
the central conductor has a welded portion which is welded to the terminal electrode and an unwelded portion which is disposed along the first surface of the receiving portion without being welded to the terminal electrode; and
a height of the weld nugget portion from the second surface of the receiving portion in a direction perpendicular to the second surface is larger than a height of the unwelded portion of the central conductor from the second surface of the receiving portion in the direction perpendicular to the second surface.

2. The coil component according to claim 1, wherein the central conductor is welded to the receiving portion and the weld nugget portion at the end portion of the wire.

3. The coil component according to claim 1, wherein the weld nugget portion is absent of a substance originated from the insulating coating layer.

4. The coil component according to claim 3, wherein the insulating coating layer is removed from an entire circumference of the end portion of the wire.

5. The coil component according to claim 1, further comprising:

- a core including a winding core portion and a flange portion that is disposed on an end portion of the winding core portion,
wherein the wire is helically wound around the winding core portion, and the terminal electrode is attached on the flange portion.

6. The coil component according to claim 5, wherein the receiving portion is located at a predetermined spacing from the flange portion.

7. The coil component according to claim 2, wherein the weld nugget portion is absent of a substance originated from the insulating coating layer.

8. The coil component according to claim 7, wherein the insulating coating layer is removed from an entire circumference of the end portion of the wire.

9. The coil component according to claim 2, further comprising:

- a core including a winding core portion and a flange portion that is disposed on an end portion of the winding core portion,

15

wherein the wire is helically wound around the winding core portion, and the terminal electrode is attached on the flange portion.

10. The coil component according to claim **3**, further comprising:

a core including a winding core portion and a flange portion that is disposed on an end portion of the winding core portion,

wherein the wire is helically wound around the winding core portion, and the terminal electrode is attached on the flange portion.

11. The coil component according to claim **4**, further comprising:

a core including a winding core portion and a flange portion that is disposed on an end portion of the winding core portion,

wherein the wire is helically wound around the winding core portion, and the terminal electrode is attached on the flange portion.

12. The coil component according to claim **7**, further comprising:

a core including a winding core portion and a flange portion that is disposed on an end portion of the winding core portion,

wherein the wire is helically wound around the winding core portion, and the terminal electrode is attached on the flange portion.

16

13. The coil component according to claim **8**, further comprising:

a core including a winding core portion and a flange portion that is disposed on an end portion of the winding core portion,

wherein the wire is helically wound around the winding core portion, and the terminal electrode is attached on the flange portion.

14. The coil component according to claim **9**, wherein the receiving portion is located at a predetermined spacing from the flange portion.

15. The coil component according to claim **10**, wherein the receiving portion is located at a predetermined spacing from the flange portion.

16. The coil component according to claim **11**, wherein the receiving portion is located at a predetermined spacing from the flange portion.

17. The coil component according to claim **12**, wherein the receiving portion is located at a predetermined spacing from the flange portion.

18. The coil component according to claim **13**, wherein the receiving portion is located at a predetermined spacing from the flange portion.
